METHOD FOR SEPARATING THIOPHENE FROM BENZENE

Albert W. Simon, McKeesport, Pa., assignor to United States Steel Corporation, a corporation of New Jersey

No Drawing. Application October 9, 1957
Serial No. 689,048

2 Claims. (Cl. 208—240)

This invention relates to the purification of coke-oven light-oil fractions such as benzene and, in particular, to a method for separating thiophene therefrom.

The standards of purity set by consumers of benzene are being raised progressively. Thiophene is one of the most troublesome impurities found in benzene because its properties are so similar to those of benzene that separation is difficult and expensive. Washing with concentrated sulfuric acid or treatment with aluminum chloride is common practice but there are serious objections to both these reagents. Accordingly, the object of my invention is to provide a simple, inexpensive method for separating thiophene from benzene.

I have found that, when benzene is distilled in the presence of a small amount of diphenylsulfone or dihydroxydiphenyl sulfone, there is a marked reduction in the thiophene content of the benzene. The distillation may be effected by conventional methods and apparatus. The amount of diphenylsulfone or dihydroxydiphenylsulfone added may be from 0.1 to 10.0% by weight of the benzene, preferably about 3%. The details of the invention will be apparent from the following explanation of typical examples thereof.

EXAMPLE 1

Ten grams of diphenylsulfone was added to 350 ml. of benzene that contained 7.4 p.p.m. of thiophene. The resulting mixture was subjected to a distillation through a four-foot packed column, the benzene being taken overhead as distillate. The thiophene analyses of the fractions collected are given in Table I. Also included in the table are the results from a control test on another sample of the same starting benzene in which all the conditions were held the same except that no diphenylsulfone was added.

Table I

Fraction Number	Volume, ml.	Thiophene Content, p.p.m.		With Diphenyl-sulfone	Without Diphenyl-sulfone
		With Diphenyl-sulfone	Without Diphenyl-sulfone		
1	50	1.1	1.7		
2	50	0.5	2.2		
3	50	0.6	2.2		
4	50	0.7	3.2		
5	50	1.2	4.0		
6	50	1.6	7.0		
	1 300	2 0.95	2 3.4		

¹ Total.

² Average.

These results show that the presence of diphenylsulfone resulted in a distillate with an average thiophene content of 0.95 p.p.m., while the distillation in which no diphenylsulfone was used gave a distillate containing 3.4 p.p.m. of thiophene. The use of diphenylsulfone thus achieved a reduction in thiophene content of 87% while

2

distillation without diphenylsulfone reduced the thiophene content only 54%.

EXAMPLE 2

5 Ten grams of diphenylsulfone was added to 350 ml. benzene which contained 508 p.p.m. of thiophene and the mixture was distilled as before. After the distillation, the distillate was analyzed for thiophene. The results are given in Table II. Also included in the table are 10 the results from a control test on another sample of the same starting benzene in which all of the conditions were held the same except that no diphenylsulfone was added. The data indicate that the diphenylsulfone is responsible for a reduction of the thiophene content of 76% while distillation without diphenylsulfone reduced the thiophene content only 40%.

Table II

Fraction Number	Volume, ml.	Thiophene Content, p.p.m.	
		With Diphenyl-sulfone	With No Sulfone
1	50	31	182
2	50	82	196
3	50	90	232
4	50	120	274
5	50	151	384
6	50	264	570
	1 300	2 123	2 306

¹ Total.

² Average.

EXAMPLE 3

35 Ten grams of dihydroxydiphenylsulfone (a commercial mixture containing mainly 4,4'-dihydroxydiphenylsulfone and some 2,4'-dihydroxydiphenylsulfone) was added to 350 ml. of benzene containing 508 p.p.m. of thiophene and the mixture distilled as before. The results of the distillation are given in Table III.

Table III

Fraction Number	Volume, ml.	Thiophene Content, p.p.m.	
		With Dihydroxy-diphenyl-sulfone	With No Sulfone
1	50	12	182
2	50	59	196
3	50	71	232
4	50	100	274
5	50	153	384
6	50	254	570
	1 300	2 108	2 306

¹ Total.

² Average.

60 The distillation from dihydroxydiphenylsulfone gave a distillate containing 108 p.p.m. of thiophene, a reduction of 79%. The benzene from a control distillation in which no sulfone was present contained 306 p.p.m. of thiophene, a reduction of 40%.

65 It will be apparent that the presence of the additive greatly enhances the thiophene removal effected by distillation. A minimum of about 0.1% of the additive is necessary to give improved removal of thiophene. A greater amount may be employed but over 10% does not give any gain in thiophene removal. Diphenylsulfone is a cheap noncorrosive compound, easily made by reacting sulfur trioxide or fuming sulfuric acid with benzene. Dihydroxydiphenylsulfone can be made from phenol in

a similar manner. Because of their high boiling points, the sulfones remain in the distillation pot. After a distillation has been completed, the thiophene concentrate may be flashed off and the sulfone recycled for further use.

The invention is also applicable to the removal of methylthiophenes from toluene and higher homologs of thiophene from xylene. A benzene-toluene-xylene fraction may also be treated in the same manner to remove thiophene and its homologs in a single distillation.

Although I have disclosed herein the preferred practice of my invention, I intend to cover as well any change or modification therein which may be made without departing from the spirit and scope of the invention.

I claim:

1. The method of separating thiophene from coke-oven light-oil fractions which comprises adding to such

fractions from 0.1% to 10% by weight, of a reagent selected from the group consisting of diphenylsulfone and dihydroxydiphenylsulfone, and distilling the resulting mixture.

5. 2. The method of separating thiophene from coke-oven light-oil fractions which comprises adding to such fractions about 3% by weight, of a reagent selected from the group consisting of diphenylsulfone and dihydroxydiphenylsulfone, and distilling the resulting mixture.
